UNITED STATES PATENT OFFICE.

BURNS DICK, OF ST. LOUIS, MISSOURI, ASSIGNOR TO WAGNER ELECTRIC MANUFACTURING COMPANY, OF ST. LOUIS, MISSOURI, A CORPORATION OF MISSOURI.

IGNITION DEVICE.

1,248,828.

Specification of Letters Patent.

Patented Dec. 4, 1917.

Application filed July 19, 1915. Serial No. 40,601.

To all whom it may concern:

Be it known that I, BURNS DICK, a subject of the King of England, residing at the city of St. Louis, State of Missouri, United States of America, have invented a certain new and useful Ignition Device, of which the following is such a full, clear, and exact description as will enable any one skilled in the art to which it appertains to make and 5 use the same, reference being had to the accompanying drawings, forming part of this specification.

My invention relates to ignition apparatus for internal combustion engines, and more 10 particularly to improved means for automatically causing the maximum explosion pressure to occur at an efficient point of the crank revolution under all load conditions.

The timing of the ignition spark and 15 therefore the time of occurrence of the maximum explosion pressure has heretofore, so far as I am aware, been placed either under the direct control of the operator or driver, or has been made dependent on the speed 20 of the engine. When placed under the direct control of the driver, the timing of the spark is usually accomplished by moving a lever operatively connected with a part of the timer and arranged to move said part 25 with relation to another and generally stationary portion of the same apparatus. When made dependent upon the speed, the movable part of the timing apparatus is placed under the control of some form of 30 centrifugal governor driven by the engine.

In the apparatus herein described, I provide a plurality of spark gaps, locate them at different distances from the main body of the compression chamber, and so constitute the electrical circuits within which said 35 spark gaps are located that the one nearest the main body of the compression chamber will be effective at low cylinder compressions while that farthest away from said main body will be effective at high cylinder compressions. This arrangement yields the desired results by virtue of the facts that at a 40 given speed the torque varies with the cylinder compression, that the resistance of a spark gap increases with the compression, and that the rate of flame propagation de-

creases as the distance of the effective spark gap from the main body of the compression chamber increases.

In the accompanying drawings, Figure 1 55 diagrammatically illustrates an embodiment of my invention. Fig. 2 shows a modification. Fig. 3 illustrates one form of a spark plug provided with a plurality of spark gaps in accordance with the invention.

Referring to Fig. 1, the compression and explosion chamber 2 of the cylinder 16 is provided with a pocket or ignition chamber 3 within which are located spark terminals forming two spark gaps 4 and 5, of which 4 is placed in close proximity to the main body of the compression chamber 2, while 5 is located back in the pocket 3. Both of these spark gaps are in circuit with the high tension winding 7 of an ignition coil, the 60 primary or low tension winding 8 of which is connected in series with the battery 9 and the interrupter 10. The interrupter is controlled by the spring 12 and is actuated by the cam 11, driven by the engine, to break the primary circuit in the usual way at the contacts 13, 14. The terminals forming the spark gap 4, which is placed near the main body of the explosion chamber 2, are directly connected to the high tension winding 7 of the spark coil, but the terminals forming the spark gap 5, which is removed from the main body of the explosion chamber, are connected to the high tension winding 7 through air-gap 6 placed outside of the cylinder 16. The magnitudes of the spark gap 5, and of the air-gap 6, and that of the spark gap 4, are so chosen that when all of them 65 are subject to atmospheric pressure, or when gaps 5 and 4 are under the influence of low cylinder compressions, the spark, following the interruption of the contacts 13 and 14, will be produced at the spark gap 4.

The operation of the arrangement shown in Fig. 1 is somewhat as follows:

The spark gaps 4, 5 and the air-gap 6 being adjusted, as above explained, spark gap 4 will be effective and spark gap 5 will be dead as long as the mechanically-produced compression in the chamber 2 is low, that is, 70 as long as the torque developed by the engine is small. With increasing torque, that

is, with increasing mechanical compression within the cylinder, and for reasons herein-after pointed out, there may be a time when sparks will be produced at both spark gaps, but, after the mechanical compression produced within the chamber 2 has further increased, the spark gap 4 will become dead and the spark gap 5 alone will be effective. When spark gap 4 is effective, the rate of flame propagation will be rapid and the explosion pressure will occur within a very short time after the separation of the contacts 13 and 14. When the mechanical compression has increased to an extent sufficient to make the spark gap 4 ineffective and to render spark gap 5 active, the rate of flame propagation will be considerably slower, due to the fact that spark gap 5 is located deep within the pocket 3 and therefore at some distance from the main body of the chamber 2. The rate of flame propagation being slower, a longer time interval will elapse between the separation of the contacts 13, 14 and the production of the maximum explosion pressure. These conditions correspond to a retardation of the spark with increasing torque, and therefore, achieve automatically the results which an ideal driver is supposed to achieve by manual manipulation of the spark timing lever.

It has been found that the resistance of a given spark gap increases with the pressure of the medium within which it is located, and it is this fact that I make use of to make the spark gap 4 ineffective and to render the spark gap 5 effective at the higher cylinder compressions. To this end all of the impedance of the circuit within which spark gap 4 is located is concentrated in said spark gap itself, whereas the impedance of the other spark gap circuit is divided between the spark gap 5 and the air-gap 6. Under these conditions an increase in cylinder compression will increase all of the impedance in the circuit of the spark gap 4, but will only increase a part of the impedance in the circuit of the spark gap 5, since a portion of that total impedance, represented by the resistance of the air-gap 6, is located outside of the cylinder and is only subject to the atmospheric pressure, which is practically constant.

Speaking generally, an impedance is expressed as

$$z = \sqrt{r^2 + x^2}$$

where r stands for the ohmic resistance and x for the reactance, which may be positive (inductance) or negative (capacity). An impedance, therefore, may consist of pure ohmic resistance, or of pure inductance, or of pure capacity, but the two latter cases are not met with in practice, for some ohmic resistance is almost always present. In the modification shown in Fig. 2, the external

air-gap 6, within the circuit of spark gap 5 which is located at some distance from the main body of the explosion chamber, is replaced by a positive reactance or inductance 15, which, I find, has practically the same effect as the gap for which it has been substituted. The operation of this modification is the same as that of the arrangement shown in Fig. 1.

The spark plug illustrated in Fig. 3, comprises a housing 17 screwed into the cylinder wall 16, and carrying an insulating body 18 clamped between it and a cap 19. The insulator 18 supports the rod 21 incased in an insulator 20 which fits loosely into a central opening through the insulator 18, passes through the insulating washer 25 and reaches into the insulating washer 26. A projection of the insulator 20 rests on the lower part of the insulator 18. All upward movement of the rod 21 is prevented by a distance piece 23 and a washer 22 clamped under the head of the rod 21. A nut 27, which screws onto the upper part of the rod 21, presses the washer 22, the distance piece 23, the insulator 20, and the insulating washers 25 and 26 against the insulator 18, holding all of these together with the rod 21 in a fixed position relatively to the insulator 18. Formed integral with the metal washer 22 is a sparking electrode 24, which forms the spark gap 4 together with the inner wall of the spark plug housing 17. A thin metal cylinder 31 is located between the insulators 18 and 20. At its lower end it carries the sparking electrode 32 which passes through a suitable opening provided in the insulator 20 and forms the spark gap 5 together with the inner wall of the spark plug housing 17. Connected to the upper end of the conducting tube 31 is the spark gap electrode 33 which passes out of the insulating body 18 through a suitable opening therein and reaches upward into an opening 6 provided in the insulating washer 25. Clamped between the insulating washers 25 and 26 is a conducting plate 30 provided with a spark gap electrode reaching downward into the opening 6 of the insulating washer 25. Clamped between the nut 27 and the thumb nut 29 is a terminal 28 which connects with the spark electrode 24, through the nuts 27, 29, the rod 21, and the washer 22. The central openings in the insulators 18 and 20 are sealed with a suitable compound, so as to prevent the escape of gases from the combustion chamber 2. The terminals 28 and 30 are both connected to one end of the secondary 7 of the ignition coil, the other end of which is grounded. The primary of this coil 8 is in circuit with the battery 9 and the mechanically-operated interrupter contacts 13, 14. It is seen that this spark plug provides two spark gaps, located in operative relation with regard to 130

the ignition chamber 2. The longer of these spark gaps is located at 4, in close proximity to the main body of the combustion chamber 2, whereas the smaller gap 5 is located deep within the pocket 3 formed by the housing of the spark plug. The larger spark gap 4 is directly connected to the secondary 7, whereas the smaller spark gap 5 is separated from the secondary 7 by the 10 auxiliary gap located in the opening 6 of the insulating washer 25. This second gap 15 is exposed to atmospheric pressure only, whereas the spark gaps 4 and 5 are subject to whatever pressure may exist within the combustion chamber 2.

It will be understood that more than two spark gaps may be provided for within each cylinder. Such spark gaps should be located at different distances from the main body of 20 the explosion chamber, and the total impedances of the various spark gap circuits and the portions of said impedances which are located outside of the cylinder, should be so chosen that at low fuel pressures ignition 25 sparks are produced at a spark gap placed near the main body of the explosion chamber, while at increasing fuel pressures said ignition sparks are produced at spark gaps located farther and farther away from the 30 main body of the explosion chamber.

Having fully described my invention, what I claim as new and desire to secure by Letters-Patent of the United States is:

1. In an internal combustion engine, the 35 combination of electrodes forming a plurality of stationary ignition spark gaps at different positions, and means preventing the production of an ignition spark at one of said gaps at the higher fuel pressures.

2. In an internal combustion engine, the 40 combination of an explosion chamber, electrodes forming a plurality of stationary ignition spark gaps, and means for causing the ignition spark to be produced at one of 45 said gaps at low fuel pressures in the explosion chamber and at a different gap at the higher fuel pressures in said chamber.

3. In an internal combustion engine, the 50 combination of an explosion chamber, electrodes forming two stationary spark gaps for igniting the fuel, said gaps being at different positions and of different lengths, and an impedance unaffected by pressure in the explosion chamber and in circuit with the 55 electrodes forming one of the spark gaps.

4. In an internal combustion engine, the 60 combination of an explosion chamber, electrodes forming two ignition spark gaps, and an impedance unaffected by pressure in the explosion chamber and in circuit with the electrodes forming one of said gaps.

5. In an internal combustion engine, the 65 combination of an explosion chamber, electrodes forming two ignition spark gaps operatively located with respect to the explo-

sion chamber, one of said gaps being farther from the main body of the explosion chamber than the other, a source of ignition voltage connected to said electrodes, and means preventing the production of an ignition 70 spark at one spark gap when the compression of the fuel in the explosion chamber is high.

6. In an internal combustion engine, the combination of an explosion chamber, an 75 auxiliary chamber communicating therewith, electrodes forming two ignition spark gaps, one of the said gaps being within the auxiliary chamber and farther from the explosion chamber than the other, a source of 80 ignition voltage connected to the said electrodes, and means preventing the production of an ignition spark at one spark gap when the compression of the fuel is high.

7. In an internal combustion engine, the 85 combination of an explosion chamber, an auxiliary chamber communicating therewith, electrodes forming two ignition spark gaps, one of the said gaps being within the auxiliary chamber and farther from the 90 explosion chamber than the other, a source of ignition voltage connected to the said electrodes, and means for causing the ignition spark to be produced at one of said gaps at low fuel pressures in the explosion chamber 95 and at a different gap at the higher fuel pressures in said chamber.

8. In an internal combustion engine, the 100 combination of an explosion chamber, an auxiliary chamber in communication therewith, electrodes forming two spark gaps for igniting the fuel, said gaps being of different length, and the shorter gap being situated within the auxiliary chamber and farther from the explosion chamber than 105 the other, and an impedance unaffected by pressure in the explosion chamber and in circuit with the electrodes forming the shorter spark gap.

9. In an internal combustion engine, the 110 combination of an explosion chamber, an auxiliary chamber in communication therewith, electrodes forming two spark gaps for igniting the fuel, said gaps being of 115 different length, the shorter gap being situated within the auxiliary chamber and farther from the explosion chamber than the other, a source of ignition voltage connected to the said electrodes, the electrodes forming one spark gap, being connected to 120 the said source in parallel circuit with the electrodes forming the other spark gap, and an impedance unaffected by pressure in the explosion chamber and in series with the electrodes forming the shorter gap.

10. In an internal combustion engine, the 125 combination of an explosion chamber, an auxiliary chamber in communication therewith, electrodes forming two spark gaps for igniting the fuel, said gaps being of differ- 130

ent length, the shorter gap being situated within the auxiliary chamber and farther from the explosion chamber than the other, a source of ignition voltage connected to the 5 said electrodes, the electrodes forming one spark gap being connected to the said source in parallel circuit with the electrodes forming the other spark gap, and a third spark gap in series with the electrodes forming the

shorter gap and positioned outside the fuel 10 chambers.

In testimony whereof, I have hereunto set my hand and affixed my seal in the presence of the two subscribing witnesses.
